SAMUEL HOWARD CARLING, OF EASTON, PENNSYLVANIA, ASSIGNOR TO CARBIN MACHINE CORPORATION, OF NEW YORK, N. Y., A CORPORATION OF NEW YORK.

WARP-BEAM-HOLDING MECHANISM FOR LOOMS.

1,318,353.

Specification of Letters Patent.

Patented Oct. 14, 1919.

Application filed June 17, 1918. Serial No. 240,409.

To all whom it may concern:

Be it known that I, SAMUEL HOWARD CARLING, a citizen of the United States, and a resident of Easton, in the county of Northampton and State of Pennsylvania, have invented certain new and useful Improvements in Warp-Beam-Holding Mechanism for Looms, of which the following is a specification.

10 My invention relates to attachments which may be readily applied to numerous styles of looms now in use, for the purpose of holding the warp-beam stationary to permit loom operators to remove the filling 15 when defects in the weaving are present.

It is well known in this art that frequently foreign matter dropping on the warp threads or imperfections in either the warp or filling cause frequent flaws or imperfections in the woven fabric. When an operator sees these imperfections she is supposed to stop the loom and remove the filling from the warp up to the perfect fabric. As 20 usually constructed, a tension is maintained 25 on the warp threads and fabric to insure the proper formation of sheds, by means of heavy weights carried by ropes which are coiled around the ends of the warp beam.

Heretofore, when it was desired to rip 30 out the filling, it was necessary for the operator to walk around to the rear of the loom and release the weights so that they rested on the floor, to release the tension on the warp, then go to the front of the 35 loom to remove the imperfect filling, and after that was accomplished to again return to the back of the loom to lift the heavy weights into position to again exert a tension on the warp, and then return to the 40 front of the loom to continue the weaving. Even skilled weavers have to rip out the filling because of flaws in the weaving, many times in the course of a day's run. It is 45 obvious that the above described method, which is the one generally in use for releasing the tension on the warp, is a slow, laborious and inefficient one and results in keeping down the output of the loom.

One of the objects of my invention there- 50 fore is to simplify the operation of releasing the tension on the warp to overcome the disadvantages of the method above set forth. Another object is to relieve the weaver of the necessity of continually lowering and raising the weights on the warp

beam to enable her to rip out filling. Another object is to provide a holding mechanism for loom warp beams that can be operated by the weaver from the position she normally occupies when weaving. A 60 further object is to provide a warp beam holding mechanism that can be readily attached to typical or standard forms of looms now in use. Other objects will be apparent from the following specification 65 when read in connection with the accompanying drawings in which:

Figure 1 is a side elevation of a loom equipped with my improved holding device.

Fig. 2 is an enlarged detail of the operating lever, viewed from the right in Fig. 1.

Fig. 3 is a diagrammatic sectional view illustrating the threading of the loom and the method heretofore used for releasing the tension on the warp threads.

Fig. 4 is a detail plan view of the warp beam showing my holding device in place thereon.

Fig. 5 is an elevation of the holding device with the front flange of the holding 80 drum sectioned off.

Fig. 6 is a horizontal section illustrating a detail of construction.

Referring to the drawings I have illustrated in Fig. 1 a typical form of silk weaving loom 1 equipped with the suitable mechanism as shown for raising and lowering the harness 2 in the usual manner to form sheds through which the shuttle 3 carried by the lay 4 is thrown by the pick 5 to carry 85 the filling threads through the sheds. The lay is operated in the usual manner by a crank 6 formed in the shaft 7, the pitman 8 connecting the crank with the lay 4.

The warp beam 9 is secured to a shaft 10 90 which is supported in V-shaped brackets 11-11 secured to the loom frame 12. Secured near each end of the shaft 10 and adjacent to the brackets 11-11 are the flanged pulleys 13-13 around each of which is coiled 100 a rope 14. To one end of the rope a heavy weight 15 is secured and to the other end a light weight 16 is likewise fastened.

The weights 15 weigh usually from fifty to 105 seventy five pounds each and act in the direction of the full line arrow in Fig. 3 to keep a tension on the warp to insure the formation of proper sheds, in a manner well known to those skilled in this art.

In the normal operation of weaving the 110

warp beam rocks back and forth each time paying off a small length of the warp which is wound thereon, the small weight 16 striking the floor when the warp beam is rocked 5 in the direction of the dotted arrow as the lay beats the filling up into the fabric. The feed roller 17 and the cloth roll 18 are operated in the direction of the arrows in Fig. 3 by the usual ratchet mechanism, not shown herein, as it forms no part of the present 10 invention.

When flaws in the fabric are discovered it is necessary to rip out the filling and this necessitates stopping the loom and releasing 15 the action of the weight 15 upon the warp to relieve the tension thereon. After the tension is released the feed mechanism for turning the rolls 17 and 18 is disengaged and the lay 4 is moved toward the harness 20 2 to permit the weaver to readily rip out the filling. Heretofore in order to relieve the tension on the warp it was necessary for the weaver to go to the back of the loom and drop the weight 15 to the floor, as 25 shown in dotted lines in Fig. 3. She then returned to the front of the loom, to remove the filling and after that was again obliged to go to the back of the loom to raise the heavy weights 15 to the position shown in 30 full lines. The continual raising of the weights put a considerable tax on the energy of weavers, who are usually girls, and resulted as well in a great loss of time.

The holding means to be now disclosed 35 does away with the necessity of the weaver raising the weights 15 or even leaving the front of the loom to release the tension on the warp.

To the end of the shaft 10 I secure by 40 means of a set screw or other suitable means a flanged holding drum 19. A flexible clamp 20 passes around the drum 19 and is normally loosely associated therewith during the weaving operation. At one end the 45 clamp 20 has an eye 21 formed thereon which is adapted to be readily slipped on and off of a pin 22 carried by a bracket 23 secured to the loom frame 12. The other end of the clamp 20 is provided with a 50 swiveled turnbuckle 24 which adjustably connects the link 25 with the operating lever 26. This lever is fulcrumed on a stud 27 (Fig. 2) having a shoulder 28 which with the coaction of the nut 29 detachably secures the supporting bracket 30 to the loom frame 12. The lever 26 is provided with lugs 31 and 32 to limit its travel by coming into contact with the bracket 30.

With a loom equipped with my improved 60 holding device when it is desired to release the tension on the warp to enable the operator to rip out filling it is only necessary for the weaver to first stop the loom and then grasp the lever 26 and pull it toward 65 her over the dead center until the lug 32

stops its movement. This action will securely lock the clamp 20 to the drum 19 thus relieving the warp beam of the torque exerted by the weights 15. The weaver then disengages the ratchet feeding mechanism 70 for the rollers 17 and 18 and moves the lay 4 toward the harness. This will cause the sheds to close and give sufficient slack in the warp to enable the weaver to remove the imperfect filling. In some instances the 75 weaver may turn the feed rolls 17 and 18 in the opposite direction to the arrows to give more slack for the ripping out operation. It is clear that at this time there is no tension on the warp as the clamp 20 holds the warp beam stationary thereby preventing the weights 15 from exerting a torque thereon. 80

It will be seen that by utilization of the improved holding device it is unnecessary for the operator to either lower or lift the 85 heavy weights or to leave the front of the loom in order to either release or restore the tension on the warp prior to ripping out imperfect filling. This results in saving a great deal of unnecessary labor for the 90 weaver and also saves a great deal of time, thereby increasing the output of woven fabric in a given time very materially.

While I have described more or less precisely the details of construction which I 95 employ I do not wish to be understood as limiting myself thereto as it is clear that changes of construction may be made by those skilled in the art without departing from the spirit and scope of my invention. 100

What I claim is:—

1. In a loom, a warp beam, means tending to normally exert a torque on said warp beam when the loom is running and means for applying a braking pressure to said 105 warp beam to hold it in a fixed position when the loom is stopped.

2. In a loom, a warp beam, a holding drum secured thereto, a flexible member for holding said drum in a fixed position when the loom is stopped, and means connected to said flexible member whereby it can be operated to clamp said flexible member to said drum.

3. In a loom, a warp beam, a holding 115 drum secured thereto, a flexible member for holding said drum in a fixed position when the loom is stopped, and means operable from the front of the loom for clamping said flexible member to the holding drum. 120

4. In a loom, a warp beam, a holding drum detachably secured thereto, a flexible member for clamping said drum in a fixed position when the loom is stopped, one end of said flexible member being detachably 125 secured to the loom frame, and means connected with the other end of said flexible member for clamping it on the aforesaid drum.

5. In a loom, a warp beam, means carried 130

5 by said warp beam for normally exerting a tension on the warp, a holding drum secured to said warp beam, a flexible member co-acting with said drum to hold the warp beam in a fixed position when the loom is stopped, and means for clamping said flexible member to the holding drum.

6. In a loom, a warp beam, means carried by said warp beam for normally exerting a 10 tension on the warp, a holding drum secured to said warp beam, a flexible member co-acting with said drum to hold the warp beam in a fixed position when the loom is stopped and means for clamping said flexible member to the holding drum.

7. In a loom, a warp beam, means carried by said warp beam for exerting a tension on the warp, a holding drum secured to said warp beam, a flexible member co-acting with 20 said drum to hold the warp beam in a fixed position when the loom is stopped and means operable from the front of the loom for clamping said flexible member to the holding drum, the said last mentioned 25 means being carried by a bracket which is detachably secured to the loom frame.

8. In a loom, a warp beam, means carried thereby for exerting a tension on the warp, a holding drum secured to said warp beam, 30 a flexible clamp associated with said hold-

ing drum, a pin secured to the loom frame, the said clamp having an eye on one end arranged to be freely slipped on and off of said pin, a link connected to the opposite end of said clamp and an operating lever 35 connected to said link for moving the clamp.

9. In a loom, a warp beam, means carried thereby for exerting a tension on the warp, a holding drum secured to said warp beam, 40 a flexible clamp associated with said holding drum, a pin secured to the loom frame, the said clamp having an eye on one end arranged to be freely slipped on and off of said pin, a link connected to the opposite 45 end of said clamp and an operating lever operable from the front of the loom connected to said link for moving the clamp.

10. In a loom, a warp beam, a holding drum secured thereto, means associated with 50 the warp beam for exerting a tension on the warp and means associated with said drum for holding said warp beam in a fixed position to relieve the tension on the warp when the loom is stopped to permit the 55 weaver to remove imperfections in the woven fabric.

In witness whereof I have hereunto signed my name.

SAMUEL HOWARD CARLING.
